PENDANT

Carl J. Kleiner, 2302 Beach, Cisco, Tex. 76437

Filed Feb. 20, 1974, Ser. No. 444,030

Term of patent 14 years

Int. Cl. D11—01

U.S. Cl. D45—16 A

FIG. 1 is a front elevational view of the pendant showing my new design;

FIG. 2 is a top plan view of said pendant;

FIG. 3 is a bottom plan view of said pendant;

FIG. 4 is a left side elevational view of said pendant;

FIG. 5 is a right side elevational view of said pendant;

FIG. 6 is a rear elevational view of said pendant;

FIG. 7 is a top perspective view of said pendant;

FIG. 8 is a bottom perspective view of said pendant;

FIG. 9 is a perspective view taken in the direction of arrows 9 in FIGS. 1 and 3; and

FIG. 10 is a perspective view taken in the direction of arrows 10 in FIGS. 1 and 3.

I claim:

The ornamental design for a pendant, as shown and described.
